UNITED STATES PATENT OFFICE

2,451,243

TRAVERSE MOTION

Otto W. Schlums, Whitinsville, Mass., assignor to
 Whitin Machine Works, Whitinsville, Mass., a
 corporation of Massachusetts

Application April 24, 1945, Serial No. 589,965

3 Claims. (Cl. 242—43)

1

This invention relates to an improved mechanism for traversing the yarn guide in a machine of the up-twister type. The invention is shown herein as applied to a winding machine of the defined type, having twister spindles and winding rolls disposed at both sides of the machine.

My invention is also shown as deriving its primary traverse motion from a drum cam as shown in detail in Helland Patent No. 2,301,699, issued to applicant's assignee November 10, 1942.

It is the general object of my invention to provide improved means for modifying the direct or primary traverse motion by either increasing or decreasing the same, and also to provide means for varying the increase or decrease progressively as the package is wound, in order to produce a package of any desired longitudinal section.

To the attainment of this general object, I provide cam means to control and vary the traverse to produce a package of a desired length and contour. By utilizing cams of selected contours, yarn packages of many desired shapes and traverses may be obtained from a single primary traverse motion. I also provide an automatic cut-out for the cam drive, and convenient means for resetting the cam.

My invention further relates to arrangements and combinations of parts which will be herein-after described and more particularly pointed out in the appended claims.

A preferred form of the invention is shown in the drawings, in which

Fig. 1 is a perspective view of my improved traverse motion;

Fig. 2 is a side elevation thereof;

Fig. 3 is a plan view, partly in section and showing the primary traverse motion;

Fig. 4 is an end elevation, partly in section, looking in the direction of the arrow 4 in Fig. 3, and

Fig. 5 is a detail end elevation of certain parts, looking in the direction of the arrow 5 in Fig. 3.

Referring particularly to Fig. 3, I have shown a fixed cam box 10 in which a drum-type traverse cam 11 is rotatably mounted on a shaft 12. Winding drums 13 and 14 are mounted on shafts 15 and 16 which are continuously rotated from any usual source of power. The shaft 16 is connected through a pinion 17, small gears 18 and 19 and large gear 20 to the drum cam 11.

A traverse block 22 is mounted to slide at each side of the cam box 10, and each block is moved by a cam roll 23 seated in the cam groove of the traverse cam 11. Consequently, the blocks 22 are simultaneously but reversely reciprocated at the

2

two sides of the machine. The parts thus far described are similar to the disclosure in the Helland patent.

The novel features of my present invention relate particularly to the improved mechanism which I have provided for transmitting motion from the traverse blocks 22 to the usual traverse rods 25, and this mechanism will now be described.

10 On each traverse block 22 is mounted a bracket 39 (Fig. 2) supporting a stud 31 on which a bell crank 32 is freely pivoted. A stud 33 at the lower end of the depending arm of the bell crank 32 is connected by a link 34 to a stud 35 fixed to the 15 end of the traverse rod 25.

A guide-block 40 (Fig. 1) is mounted on a cross shaft 41 supported in fixed bearing brackets 42, and the block 40 is provided with a guideway or groove 43 to receive a roll 44 (Fig. 1) in the 20 end of the horizontal arm of the bell crank 32. The parts just described are duplicated at opposite sides of the machine, as clearly shown in Fig. 1.

If the guide groove 43 in the block 40 is horizontal and parallel to the path of movement of the traverse block 22, the bell crank 32 will receive no angular movement on its stud 31 and the movement of the traverse rod 25 will be identical and simultaneous with the movement of 30 the traverse block 22. The parts are shown in this relation in Fig. 2.

The angular position of the guide-block 40 is determined by a lever 46 having a roll 47 engaging the periphery of a contoured cam 48. A 35 spring 49 (Fig. 1) maintains the roll 47 firmly against the cam 48. The lever 46 is pivoted at 46a to an arm 40a integral with the guide-block 40. The lever 46 also has an adjustable bolt-and-slot connection 46b with the arm 40a.

Feed mechanism (to be described) gradually 40 rotates the cam 48 during the winding of the yarn package and by so doing, varies the angular position of the guide-blocks 40 at the opposite sides of the machine. If the blocks 40 are displaced anti-clockwise, as viewed in Fig. 2, the traverse rod 25 will receive the full sliding motion of the traverse block 22, less a certain reduction when the bell crank 32 receives an anti-clockwise movement from the guide-block 40 as 45 the block 22 and bell crank 32 move to the left in Fig. 2. The same reduction will be made at the right-hand limit of traverse.

The combined effect of these two motions is to 50 reduce the traverse of the rod 25 with respect to the traverse of the block 22, and it will be obvious

that this reduction in traverse may be increased or decreased by changing the shape of the control cam 48. Changes in length and contour of package may be obtained by substituting a different cam 48, and certain differences in length and contour may also be attained by changing the adjustment of the cam roll lever 46 on the arm 40a.

Feeding mechanism

Provision is made for advancing the cam 48 anti-clockwise a slight amount each time the traverse block 22 is moved to the left in Fig. 2. For this purpose, a ratchet 50 (Fig. 2) is mounted on a fixed stud 51 and is intermittently fed anti-clockwise by a feed pawl 52 on a feed lever 53 having an upward extension 54. The extension 54 is normally held against a stop pin 55 by a spring 56 and is engaged by a stud 57 each time the traverse block 22 moves to the left. The stud 57 is adjustable in a slot 58 so that the swing of the lever 53 may be selectively varied.

A worm 60 rotates with the ratchet 50 and meshes with a worm gear 61 on a worm shaft 62, which in turn is rotatable in bearings in a cradle 63 pivoted to swing about the axis of the ratchet 50 and worm gear 60. At its left-hand end, as viewed in Fig. 2, the worm shaft 62 has a worm 64 normally held in mesh with a worm gear 65 by a tension spring 66. A geared connection is thus provided between the ratchet 50 and the contoured cam 48, and the cam will be advanced anti-clockwise each time the stud 57 is moved to the left with the traverse block 22.

As the winding proceeds, the angle of the guide-block 40 will be progressively shifted, thus varying the effective traverse of the traverse rod 25 and correspondingly varying the contour of the yarn package. By varying the shape of the cam, the package may be given conical ends of different inclinations or the outer corners of the package may be rounded or beveled at any desired angle.

Any suitable guiding devices may be mounted on the traverse rod 25. In Fig. 5 I have shown a typical arrangement in which the yarn Y is drawn upward from a spool S (Fig. 2) mounted on a twister spindle 70. The yarn passes through a guide 71, over a fixed guide-rod 72, and over a pivoted guide member 73 which is mounted on the traverse rod 25. The yarn is then wound on a package P mounted on a swinging arm 75 and frictionally engaging the driving roll 14. These parts are all of usual commercial construction and form no part of my invention.

The abrupt drop in the cam 48 (Fig. 2) makes it necessary to prevent complete rotation thereof in an anti-clockwise direction, and consequently I omit certain teeth in the worm gear 65 as indicated at 65a (Fig. 2). When this portion of the worm gear becomes associated with the worm 64, rotation of the cam immediately ceases.

In order to reset the cam 48, I provide the cradle 63 with a depending arm 80 (Fig. 1) having a stud 81 engaged by a bent lever 82 pivoted at 83 (Fig. 4) on an arm 84 supported by a fixed stud 85. The upper end of the bent lever 82 is engaged by a disc 86 on the inner end of a sleeve 87 slidable on the stud 85 and connected to the cam 48 by a pin 88 extending through a hole in the disc 86.

When it is desired to reset the cam 48, a handle 90 is connected to the sleeve 87 and the sleeve 87 and disc 86 are pushed inward, thus swinging the bent lever 82, depressing the cradle 63 and

disengaging the worm 64. This movement is against the tension of the spring 66 by which the worm and worm gear are normally held in engagement. If the handle 90 is then turned clockwise while axial pressure thereon is maintained, the cam 48 may be restored to its initial position and, on release of the handle, the parts will resume normal driving relation.

By varying the shape or size of the cam 48 or the setting of the parts of the lever 46, the guide-blocks 40 may be displaced clockwise instead of anti-clockwise from the horizontal, in which case the travel of the traverse rod 25 and the yarn guide 73 may exceed the normal travel of the traverse block 22 and a bobbin may be produced in which the outer layers of yarn are longer than the inner layers. Such a yarn package has marked advantages under special conditions.

Having described the details of construction of my improved traverse motion, it will be seen that I have provided a very flexible motion by the use of which a yarn package of any desired contour may be readily obtained from a standard traverse motion such as is disclosed in the Helland patent cited. The flat disc-like cams 48 may be easily and cheaply produced and may be readily modified to provide exactly the package contour found most desirable for a given purpose.

A yarn package having flat ends may be produced by removing the pin 57, so that the cam 48 is not fed. The length of the flat-end package to be thus produced may be varied by changing the setting of the guide-blocks 40. The longest practical package would be obtained by turning the blocks 40 clockwise 45° from the horizontal, and the shortest package would be obtained by turning the blocks 45° anti-clockwise. Any desired length between the longest and shortest could be obtained by intermediate settings of the blocks 40.

Tapered and rounded ends, as previously explained, can be obtained by feeding the cam 48 during the building of the package, and further variations may be obtained by reversing the cam 48. The contour of the cam may be modified to take care of the gradual change in yarn tension as the yarn is unwound from a rotating supply package. These tension changes have previously caused the ends of the wound packages to be more or less irregular and unsatisfactory. An ideal shipping package for most purposes has a regular taper at each end but with a slight rounding at the outer corners. Such a package may be readily secured by using my improved traverse motion.

Having thus described my invention and the advantages thereof, I do not wish to be limited to the details herein disclosed, otherwise than as set forth in the claims, but what I claim is:

1. In a yarn traverse motion, a traverse rod, a traverse block having a fixed straight-line reciprocating motion, a lever mounted on said block and connected to said rod, a guide-block for said lever, a cam controlling the angular setting of said guide-block, means including a gear for feeding said cam progressively as the winding of the yarn package proceeds, and said gear having certain teeth omitted and being thereby rendered effective to stop the feed of the cam at a predetermined point.

2. In a yarn traverse motion, a traverse rod, a traverse block having a fixed straight-line reciprocating motion parallel to said traverse rod, a lever mounted on said block and connected to said traverse rod, a guide-block for said lever

mounted on a fixed pivot and having a guideway therein, a roll on said lever seated in said guideway, a cam shaft, a cam on said shaft, a cam roll engaged by said cam, a lever on which said cam roll is mounted, an arm integral with said guide-block and to which said lever is pivoted, a bolt-and-slot connection between said lever and said arm adapted to secure said parts in selected angular relations, whereby the operative effect of said cam may be modified, and means to feed said cam progressively as the winding of the yarn package proceeds.

3. In a yarn traverse motion, a traverse rod, a traverse block having a fixed straight-line reciprocating motion, a lever mounted on said block and connected to said traverse rod, a guide-block for said lever, a cam shaft, a cam on said

shaft having a progressively increasing radius, a cam follower associated with said guide-block and engaged by said cam to control the angular set of said guide-block, and means to angularly advance said cam shaft and cam progressively as the winding of the yarn package proceeds.

OTTO W. SCHLUMS.
